WHEEL COVER

Irvin W. Rybicki, Bloomfield Hills, Mich., assignor to General Motors Corporation, Detroit, Mich., a corporation of Delaware

Filed Sept. 28, 1964, Ser. No. 81,903

Term of patent 7 years

(Cl. D14—30)

URE 5;

I claim:

The ornamental design for a wheel cover, substantially as shown.
